ATTORNEYS.

UNITED STATES PATENT OFFICE.

GEORGE UDELL, OF PROVIDENCE, RHODE ISLAND.

DESIGN FOR A DOCTOR-BLADE FOR PRINTING-MACHINES.

SPECIFICATION forming part of Design No. 29,922, dated January 3, 1899.

Application filed November 26, 1898. Serial No. 697,564. Term of patent 14 years.

To all whom it may concern:

Be it known that I, GEORGE UDELL, a citizen of the United States, residing at Providence, in the county of Providence and State 5 of Rhode Island, have invented and produced a new and original Design for a Doctor-Blade for Printing-Machines, of which the following is a specification, reference being had to the accompanying drawing, forming a part thereof, 10 which represents a plan view of a doctor-blade embodying the features of my design.

The design consists in a blade the upper

and lower longitudinal edges whereof are in a measure concaved, thereby causing the end portions of the blade to appear much wider 15 than the central portion, while the ends of the blade are convexed.

I claim—

The design for a doctor-blade for printing-machines, herein shown and described.

GEORGE UDELL.
